CLAIM

The ornamental design for a purse, as shown and described.

DESCRIPTION

FIG. 1 is a front perspective view of a purse;

FIG. 2 is a rear perspective view of the purse;

FIG. 3 is a top view of the purse;

FIG. 4 is a bottom view of the purse;

FIG. 5 is a left side view of the purse;

FIG. 6 is a right side view of the purse;

FIG. 7 is a front view of the purse; and,

FIG. 8 is a rear view of the purse.

The broken lines in the drawings illustrate portions of the purse, including stitching, that form no part of the claimed design.
